UNITED STATES PATENT OFFICE

2,475,182

ELECTRIC INSECT DESTROYER

Allen J. Gardenheur, Waynesboro, Pa.

Application January 3, 1944, Serial No. 516,801

3 Claims. (Cl. 43—112)

1

This invention relates to improvements in fly and insect electrocutors.

The primary object of this invention is the provision of an electrocutor of cage-like structure with which a source of illumination is associated for the purpose of attracting flies or insects into the electrocuting range.

A further object of this invention is the provision of a low cost, fool proof and weather resistant electrocutor which is extremely durable and low in maintenance cost.

Other objects and advantages of this invention will be apparent during the course of the following detailed description.

In the accompanying drawings, forming a part of this specification, and wherein similar reference characters designate corresponding parts throughout the several views.

Figure 1 is a perspective view of the improved electrocutor.

Figure 2 is a diagrammatic representation of the wiring circuit.

Figure 3 is a vertical cross sectional view taken through the improved electrocutor.

Figures 4 and 5 are cross sectional views taken substantially on the respective lines in Figure 3 of the drawings.

In the drawings, wherein for the purpose of illustration is shown only a preferred embodiment of the invention, the letter A may generally designate the improved electrocutor, which may include a framework B consisting of metal top and bottom members C and D and insulating supporting posts E for supporting the electrical grid F. A transformer G is supported upon the framework and with the same is associated an improved cover arrangement H.

The grid supporting posts E are of porcelain or other insulation material spirally grooved in the same manner as set forth in my co-pending application, Serial Number 516,800, filed January 3, 1944. The supporting members or posts E are adapted to be vertically positioned and to that end individual bolts 20 extend through the passageways thereof. The heads of the bolts lie beneath the base D of the framework B, and the nut ends 21 thereof are clamped upon the top metal wall C.

The base D is preferably of stamped metal including a wall 23 and depending flanges 24. The former has an opening 26 therein through which the electrocuted insects and flies drop through or into the base D.

The metal top wall C is suitably apertured to receive the threaded ends of the bolts 20; the

2

nuts 21 being clamped thereon. Said wall C is provided with upwardly extending inwardly convergent flanges 30, separated from each other at the corners thereof for accurate interfitting in the lower end of the frusto-pyramidal shaped cover or roof H.

The grid F comprises two wires, designated generally at 35 and 36, spirally wound in the grooves of the posts or members E so that the adjacent strands of wire at each side portion of the grid are formed of different wires. This effect is secured by winding each wire upon the posts so that it is turned in the alternate grooved portions of the spiral groove of each post; the intermediate grooved portions of the spiral groove receiving the turns of the other wire. These two wires are not in contact at any point and they are electrically charged, as will be hereinafter described, with the current of opposite polarity.

20 In the specific example shown it is noted that four of the posts E are provided in a rectangular arrangement, but of course I may provide any described number. The grid forms a cage-like enclosure.

25 In each of the side grid portions the strands are absolutely parallel and uniformly spaced to insure an air gap which is just beyond the breakdown voltage. The gauge of the wire is such that while the wire is bendable it is inherently 30 stiff and will flex only under appreciable manual effort. So as to horizontally position and maintain true parallelism of the strands and to tension the same so that the parallel strands lie exactly perpendicular to the axes of the posts, 35 each strand for each side of the grid at each of the posts E is crimped at 40. The crimps are straight and also lie in parallelism so as to maintain a uniform air gap. It is to be noted from the wiring diagram in Figure 2 that the two 40 wires 35 and 36 are not in contact at any point. The ends of each of the wires at certain of the posts D completely loop the bars and are soldered to themselves.

45 The transformer G is of the laminated core gas tube type and detachably supported upon the top wall C by means of four vertically positioned metal legs 45. These legs have angled feet abutting the top surface of the wall C through which they are secured to the wall by screws 46. The transformer G, shown diagrammatically in Figure 2, includes a primary winding 50, the ends of which are connected to wires 51 having a connecting plug 52 thereon. The secondary winding 53 has wires 54 and 55 leading therefrom respectively

connected with the wires 35 and 36, as by soldering at 57.

In the electrocutor the air gap measures one quarter of an inch in each of the side grid portions of the complete grid F. Under such circumstances, the primary winding is 115 A. C. and the secondary is 2,000 volts-18 milliamperes.

In my improved electrocutor I provide a lamp socket 70 detachably supported as by bolts 71 upon the lower surface of the wall C; the socket within being positioned within the cage-like arrangement of the grid and being adapted to receive a bulb 72 which may be inserted into the socket through the opening 26 in the bottom wall or base of the housing structure.

Current to the bulb 72 is supplied through lead lines 73 connected with the wires 51 above mentioned, as shown diagrammatically in Figure 2.

The roof structure 4 is of frusto-pyramidal shape including a top wall 80 and downwardly divergent side walls 81; each of the latter being adapted to receive one of the flanges 30 in abutting relation inside thereof, and being provided with screws 82 to detachably connect the walls 81 to the wall structure C.

The top wall 80 is provided with a hollow nut attached bushing 85 through which the wires 51 extend; the bushing structure including a supporting ring 87 to enable the support of the electrocutor upon a suitable hanger or hook.

It is to be noted that the transformer is completely hidden from sight and supported upon the top wall structure C within the roof H, where it is readily accessible at all times.

It will be apparent from the foregoing that adjacent strands of the side grids of the grid structure will be supplied with current of opposite polarity. There is no possibility of leakage of the high tension voltage because the air gap at all points in each of the side grids is just beyond the breakdown voltage.

Should a fly or insect pass through the gap at any point in the grid, a circuit will arc through the fly or insect and it will be electrocuted.

Various changes in the shape, size and arrangement of parts may be made to the form of invention herein shown and described, without departing from the spirit of the invention or the scope of the following claims.

I claim:

1. In an electrocutor the combination of a framework including a base, a top wall, insulation posts secured at opposite ends to the base and top

wall in a vertical arrangement, said posts being of a number greater than two, and electrically conductive stiff but manually bendable wires wound around said posts and extending between

5 the posts to provide electrocuting grids, said wires having crimps adjacent to said posts at each side of the frame to provide tensioned horizontally positioned parallel strands at each grid, defining uniform air gaps therebetween.

10 2. In an electrocutor the combination of a framework including a base, a top wall, insulation posts secured at opposite ends to the base and top wall in a vertical arrangement, said posts being of a number greater than two, and a pair of stiff

15 but manually bendable wires wound around said posts in alternating strand providing relation, said wires having crimps adjacent to said posts at each side of the frame to provide tensioned horizontally positioned parallel strands at each side of

20 the grid defining uniform air gaps therebetween, and means for charging said wires with current of opposite polarity.

3. In an electrocutor the combination of a metallic base, a metallic top, a plurality of spirally

25 grooved hollow insulation posts, bolts extending thru said posts and secured at opposite ends thereof to said base and top wall, and relatively stiff but bendable wire wound in the grooves from post to post provide grids between adjacent posts,

30 the strands of wire forming said grids each being crimped therein adjacent each of said posts to horizontally position the strands in uniform air gap providing relation.
